PHOTOENGRAVING SCREEN AND PROCESS
OF PRODUCING SAMECharles E. Benson, Los Angeles, Calif., assignor
to Los Angeles Engraving Company, Inc., Los
Angeles, Calif., a corporation of California

Application May 22, 1935, Serial No. 22,860

3 Claims. (Cl. 95—81)

This invention relates to screens for use in the art of photo-engraving and a new and novel process of producing same.

The invention is more particularly directed to 5 half-tone and mezzograph screens, the former characterized by symmetrically placed, conventional, opaque and transparent square dots of uniform size as distinguished from a mezzograph screen which is made so as to produce grains of 10 different degrees of fineness and not symmetrically placed. Such screens are employed for the purpose of obtaining fine tonal and artistic effects in half-tone prints produced therefrom. A half-tone screen structurally embodies a grating or 15 mesh consisting of clear finely polished glass panels, each ruled with parallel lines etched into the glass and filled in with an opaque substance, both pieces being connected together to dispose the rulings on one glass at exact right angles to the 20 rulings on the other, leaving transparent square apertures between the rulings the size of which will be determined by the distance apart of the respective rulings. As distinguished from the features which characterize a halftone screen, a 25 conventional mezzograph screen is characterized by a grain structure in various degrees of grain fineness, the screen glass being coated with a resistant, which is treated so it will reticulate and produce a smooth, even, grained structure 30 with no opaque filling between the grains, as their form is such that light is refracted in passing through them to provide corresponding grain structures of high lights and shadows on the negative.

35 It has been discovered that any conventional screen of the kind above referred to can be employed with which to produce a new, novel and useful screen having the form of a photographic composite of such conventional dots or grains, 40 as the case may be, and a pattern of some suitable design, such as the weave of textile material, that is to say, canvas, monk's cloth or other pattern producing surface, whether of a textile nature or not, and that a halftone print of a copy 45 made through such composite of these two structures will be enhanced to an appreciable degree, the tonal effect and render to the eye the impression that the reproduction is a print of a copy on canvas or other foundation or pattern 50 material.

It is therefore an object of the invention to provide either a dot screen or a grain screen which has photographically superimposed thereon, so to speak, a photographic image of a particular distinctive pattern, upon which the photographed

subject or copy will itself appear as having been directly painted thereon. In this manner, the copy or subject from which a halftone is to be made can be placed in front of a copy board and photographed to provide a halftone negative 5 in the customary manner, except that instead of using a dot screen, use is made of a screen which is a composite of the pattern to be reproduced and a dot screen.

In the accompanying drawing, wherein has 10 been illustrated a preferred embodiment of the invention,

Figure 1 is a plan view of a conventional cross line screen ordinarily employed in the making of a halftone negative;

Figure 2 is a detail view of a section of pattern providing material;

Figure 3 is a schematic illustration wherein a conventional halftone screen has been placed as usual in front of a sensitized plate in a process 20 camera and the pattern material positioned on the copy board to be photographed onto the plate through said conventional cross line screen;

Figure 4 is a view of two half-tone pictures as produced by the photo-engraving screen and 25 process embodying this invention.

Referring more particularly to the accompanying drawing, wherein like reference numerals indicate similar parts throughout the several views, 5 indicates a conventional process camera; 6 a sensitized plate in plate holder 7, and 8 a conventional halftone screen. A copy board 9 of usual construction is shown at 10 and mounted thereon is a pattern material 11, such as canvas, monk's cloth or any other well known pattern 35 providing material upon which a light can be projected from a lamp 12 as is the practice when photographing a copy.

Assuming that the screen 8 has been properly adjusted relative to the plate 6, and that the 40 camera has been focussed for size and sharpness of the pattern material, exposure can now be made the same as when making a halftone negative.

From a negative thus made, the same being a 45 composite of a conventional dot screen and a pattern material such as described herein, a positive can now be made and subsequently employed in lieu of the customary dot or cross lined screen. A copy from which a halftone is to be made can 50 now be photographed directly through this composite screen, and, as first above described, a print will appear to the eye as having been made from a copy on a particular pattern material. The degree of perceptibility of the pattern will be 55

quite prominent in the print and the halftone dots will serve to reproduce tones the same as an ordinary halftone screen characterized by small transparent squares, all as shown in Figure 4 by 5 the actual half-tone pictures 13 and 14 produced from different composite screens made in accordance with the process of this invention.

I claim:

1. The herein described method of making a 10 photo-engraving screen which comprises exposing a sensitive photographic plate through a conventional photo-engraving screen and photographing upon the entire sensitized surface of the plate, the surface images of portions of a material 15 of predetermined kind, whereby to provide a negative which is a composite of the images of the screen characterizing portions of the conventional screen and the images of the surface portions of the aforestated material, then making a 20 positive from the negative adapted to be used in the making of prints in place of a conventional screen, so that the subject in the print when photographed upon a sensitized plate through said positive will appear as though mounted upon 25 a backing having the surface characteristics of the aforestated material of predetermined kind.
2. The herein described method of making a 30 photo-engraving screen which comprises exposing a sensitive photographic plate through a conventional photo-engraving screen and photographing upon the entire sensitized surface of the plate, the surface images of portions of a fabric

material of predetermined kind, whereby to provide a negative which is a composite of the images of the screen characterizing portions of the conventional screen and the images of the surface portions of the aforestated material, then making 5 a positive from the negative adapted to be used in the making of prints in place of a conventional screen, so that the subject in the print when photographed upon a sensitized plate through said positive will appear as though mounted upon 10 a backing having the surface characteristics of the aforestated material of predetermined kind.

3. The herein described method of making a photo-engraving screen which comprises exposing a sensitive photographic plate through a conventional photo-engraving screen and photographing upon the entire sensitized surface of the plate, the surface images of portions of a woven material of predetermined kind, whereby to provide a negative which is a composite of the 20 images of the screen characterizing portions of the conventional screen and the images of the surface portions of the aforestated material, then making a positive from the negative adapted to be used in the making of prints in place of a conventional screen, so that the subject in the print when photographed upon a sensitized plate through said positive will appear as though mounted upon a backing having the surface characteristics of the aforestated material of pre- 25 determined kind.

CHARLES E. BENSON.
